ELECTRON DISCHARGE DEVICE

Karl Steimel, Berlin, Germany, assignor to Telefunken Gesellschaft für Drahtlose Telegraphie m. b. H., Berlin, Germany, a corporation of Germany

Application June 29, 1934, Serial No. 732,991
In Germany July 5, 1933

7 Claims. (Cl. 250—27.5)

My invention relates to an electron discharge tube of the multi-grid type and having a plurality of discharge paths extending from the cathode, each discharge path being at least partially controlled by a common control electrode.

In radio receivers employing the superheterodyne method of reception, the problem is to combine two different oscillations; that is, the oscillations produced by a distant signal received by the antenna and usually amplified in a preceding stage, and the local oscillations produced in the receiver proper for providing the heterodyne action, so that the resulting intermediate frequency oscillations are modulated in the same manner as the distant signal. This action is usually accomplished in a so-called mixer tube used in various well known circuits. In order to simplify the receiver, it has been previously proposed to provide the function of the local oscillator (heterodyne) and that of the mixer stage within a single tube. This is usually accomplished by using a tube containing several grid electrodes between a cathode and an anode. Upon one of the grids, for example, that next to the cathode, the modulated distant signal may be impressed. By means of two further grids coupled to each other usually by a feed back arrangement, the local heterodyne oscillation is produced, and the latter together with the received signal results in the desired intermediate frequency oscillations which appear in the anode circuit. It is important to generate the local oscillations independently of control by the input or signal voltage. To this end, a screen grid is placed between the control grid and the electrodes serving for the production of the local oscillations. In this way a tube having six electrodes (hexode) is obtained, which has positioned in the discharge path between the cathode and anode four electrodes thru which current passes. If necessary, still another screen grid (suppressor grid) could be placed in front of the anode, and some other sequence of the electrodes connected to the input circuit and those serving for the production of local oscillations could be arranged.

The above method of producing oscillations in the current path controlled by the alternating input or signal voltage has a number of practical disadvantages, which become particularly noticeable if the same tube is used for volume control, for example, for the purpose of compensating for fading phenomena due to atmospheric conditions. In this case, the electron current is eventually blocked to such an extent, by the action of the control electrode, that the current density neces-

sary for the production of the local oscillations, is no longer available.

Similar conditions exist in other circuits. This is true, for example, in a high frequency amplifier stage made regenerative for example by means of feed back, and whose amplification factor is controlled at the same time by varying the grid voltage. Also the so-called "homodyne circuit" must be mentioned in this connection. As is well known this circuit is characterized by the heterodyning of the received signal on an oscillation produced in the receiver and of a frequency conforming with that of the carrier wave. These last two arrangements differ from the above mentioned mixer circuit in intermediate frequency principally by the value of the frequency with which self excitation or regeneration is produced.

It is an object of my invention to provide an improved tube which will avoid the above disadvantages, particularly if the tube is used for volume control and which has a more favorable electrical separation between the parts of the tube generating the local oscillations and the parts performing the actual mixing operation by constructing a tube having two separate discharge paths from a common cathode and at least one grid electrode common to both discharge paths.

Multi-grid tubes have been provided in which all electrodes are in the same discharge path, or in which the discharge paths are entirely separated except for a common cathode. However, such tubes are not adapted to successfully perform the functions outlined above. It has also been suggested, to place around a single cathode two electrode systems adjacent each other, and to conductively connect, or to constructively join one of the electrodes or several of the electrodes in the different systems. The present invention differentiates over the arrangement described in that the two discharge paths are not placed side by side, but extend in different directions, preferably displaced 180° to each other. This provides the advantage of a more favorable condition for less coupling of the two systems without the use of special shielding devices, and the further advantage that a short length construction of the tube is obtained, in view of which the electrode system can be easier manufactured and mounted. Furthermore, such an electrode system is practically free from microphonic effects.

The novel features which I believe to be characteristic of my invention are set forth with particularity in the appended claims, but the invention itself will best be understood by reference to the following description taken in connection

with the accompanying drawings in which Figure 1 is a schematic view of an electron discharge device embodying my invention. Figure 2 is a diagrammatic showing of a circuit embodying the tube shown in Figure 1. Figure 3 is a schematic transverse cross section taken thru a tube made in accordance with my invention and showing the electrode arrangement. Figures 4 and 5 are schematic transverse cross sections of modifications of the tube shown in Figure 3. Figure 6 is a diagrammatic showing of a circuit embodying a still further modification of the tubes shown in the preceding figures.

As shown in Figure 1, the tube is provided with a glass bulb or envelope 1, containing an electron emitting cathode 2, which may be directly or indirectly heated. The cathode is enclosed by a grid like electrode 3 preferably of cylindrical shape. The other electrodes are positioned in different current paths. The auxiliary anode 4 is placed on one side of the cathode and grid 3, and on the other side is placed the screen grid 5, the control electrode 6, a second screen grid 7 and the main anode 8.

With a tube of the type described the circuit shown in Figure 2, as well as others, can be used. The input circuit comprising the inductance L and condenser C fed from the antenna A or from a proceeding stage, is connected between the cathode 2 and the control grid 6, which is negatively biased by means of the battery E_g . If it is desired to provide automatic volume control, the control grid bias may be made variable and to depend upon the input amplitude in any well known manner. In this case the grid 5 is designed to have a variable mu or amplification factor. The two screen grids 5 and 7 may be operated at the same positive bias. They are electrically connected to each other within the envelope or within the base thereby saving one base pin. The auxiliary anode 4 connected to the positive side of the anode battery E_a thru the inductance L' , is coupled by means of this inductance to the tuned circuit comprising inductance L and condenser C_1 connected in the circuit of grid 3. Since the grid 3 is in the main current path between the cathode 2 and the main anode 8, the discharge current between the cathodes and the anode 8 will be controlled by the grid 3 to vary the frequency of oscillation produced in the auxiliary discharge circuit, and at the same time will be controlled by the signal impressed on the control grid 6. Regarding the operation of the tube, it is pointed out that the voltage of the electrode 6 controls the current distribution between the anode 8 and the first screen grid 5. In other words, the mutual conductance S or steepness of the anode current characteristic will be affected by the voltage on electrode 6. Since the presence of the second screen grid 7 makes reaction of the alternating anode potential upon the control performance so slight that it can be disregarded, the condition exists that the alternating plate current J_a is equal to the product of the heterodyne voltage E_u (local oscillator voltage) impressed upon grid 3 and the mutual conductance S (that is $J_a = SE_u$). Since, however, S is also a function of E_g (E_g = alternating input voltage), the heterodyne voltage E_u and the input voltage E_g have a multiplying effect upon the discharge current. In this way there is formed the sum and difference of the frequency of input wave or signal and the heterodyne frequency, which appears in the anode circuit and is transferred to the subsequent amplifier, which may

be connected across the oscillatory circuit comprising inductor L_2 and condenser C_2 tuned to the intermediate frequency.

In the oscillatory grid circuit L_1 , C_1 there is connected in series with the coil L_1 , a resistor R bridged by a condenser C_3 for the following reason: It is desirable to be able to readily initiate the heterodyne oscillations and at the same time it is necessary to maintain the amplitude of the oscillations at a constant value. The resistor R performs both of these functions. Before oscillation starts, grid 3 is at cathode potential, and since the steepness of the grid voltage plate current curve is the greatest under these conditions, oscillations are easily built up. As soon as the oscillations are generated, a grid current producing a voltage drop across resistor R, begins to flow, and consequently the working point or grid bias of the tube will be shifted into the region of negative grid bias thereby stabilizing and limiting the amplitude of the oscillations.

It may furthermore be of advantage to provide the two halves of grid 3 with a different mu or amplification factor. For producing oscillations a high mu is desirable since in this case small feed back voltages suffice, and the steady state oscillation amplitude can be adjusted to have small values, especially by means of the action of the resistor R mentioned above. However, for the other discharge path the total useful control range is of great importance. This range must be large as compared with the total useful control of the discharge path serving for the production of local oscillations, in order that the heterodyne oscillations do not cause overload and produce distortions, which distortions must be avoided under all conditions because of the upper harmonics thereby developed. For this reason different values of mu (amplification factor) are chosen for the two grid halves. The mu at the side of the local oscillation system is made from 5 to 10 times as large as the mu at the side of the mixing system. The mu meant is that with reference to the electrode directly following the respective grid half, thus in the one case, to the mu between electrodes 3 to 4, and in the other case between electrodes 3 to 5. The requirement of a different mu is especially easy to accomplish if the grid 3 is composed of two halves which are conductively connected to each other, since in this case the current penetration (determined by the width of the mesh or the pitch of the grid) as well as the distance from the cathode can be made of different magnitude.

Figure 3 shows a transverse cross section of the electrode system constructed in accordance with my invention. In the glass envelope 1 there is placed the cathode 2, preferably indirectly heated, and enclosed by a concentric cylindrical grid 3. In order to bring the grid surface as close as possible to the cathode surface, it is shaped as shown and is secured to the supporting rods 10 by means of two ribs or fins 10. By this construction the production of a homogeneous field is made possible in the proximity of the cathode. At the same time, the ribs or fins 10, which act as shields, improve the decoupling of the two discharge paths by their shielding action. The auxiliary anode 4, having the shape of a flat or curved plate, is placed at one side of the control grid. On the other side the electrode 3 is followed by the first screen grid 5, the control grid 6, the second screen grid 7 and the main anode 8. These electrodes are formed for example, as plane surfaces parallel to each other.

Since, as stated above, the two screen grids 5 and 7 can have the same potential applied to them, they can be structurally combined, and may for example have the shape of a box formed of a 5 metal mesh, and be mounted on two longitudinal- 10 ly disposed parallel supports 12. Within this box is arranged the control electrode 6 supported by two columns 13. In order to prevent a deviation of the electrons in the direction of the supports 10 15 12, the columns 13 are formed of solid sheet metal strips.

A modification of the construction of the electrode system is shown in Figure 4. The electrode system mounted within the glass envelope 20 contains a so-called "flat cathode" 21 preferably of rectangular cross section. The advantage of the flat cathode is that a very homogeneous field distribution is formed around it, and that the control electrode can be very closely disposed to the 20 cathode because it can be stretched out between the supporting wires. In addition the flat cathode insures a favorable decoupling of the two discharge paths. The control grid 22 has the shape of a box of rectangular cross section, formed of 25 two halves having a different width of the mesh. The same box shape is also used for the double screen grid 23 whose surface is twice passed by the discharge current. The second control grid 24, as well as the anode 25, has a U-shaped cross 30 section, which promotes the formation of a homogeneous field and permits the electrodes to be mounted in the center plane of the electrode system. The auxiliary electrode 26 is shaped as a flat plate.

The modification shown in Figure 5 shows the electrode system provided with a suppressor grid. For the sake of simplicity the same reference characters have been used for the electrodes corresponding with those of Figure 4. The added 40 suppressor grid 27 performs several functions. A negative potential with respect to the anode 25, preferably the cathode potential, is applied to the suppressor grid. Because of this, the suppressor grid prevents secondary electrons from 45 the anode from reaching the preceding screen grid 23. At the same time, the mu of the control grid 22 with respect to the anode 25 is increased and therefore the anode reaction is decreased, i. e. the plate impedance is increased. The suppressor grid furthermore permits the application to the screen grid 23 of the same 50 direct voltage as that applied to the anode 25, while heretofore a lower voltage was usually impressed upon the screen grid, this voltage ordi- 55 narily being obtained from a voltage divider. As shown in Figure 5, the suppressor grid is likewise formed into a box shape and surrounds the auxiliary electrode 26, thus including the discharge path between the cathode and the auxiliary an- 60 ode. Consequently a favorable screening towards the outside is produced, so that the discharge is no longer influenced by disturbing exterior fields.

A further embodiment of a tube coming within the scope of the present invention, is schematically represented in the circuit diagram of Figure 6. For the sake of simplicity, identical reference characters have been used here for the elements conforming with those in Figure 2. The novel feature in the tube is in that the two halves 70 3', 3'' of the innermost grid 3 are not conductively connected to each other, but capacitively by means of a condenser K. The condenser is suitably mounted in the interior of the tube or in the socket, and each grid half is provided with an insulated lead. This measure appears to be expedi-

ent, where the two halves 3', 3'' altho having the same alternating voltage applied to the two halves, have different direct voltages applied to them. This case occurs when the innermost grid 3' is intended to be used for volume control. The high frequency voltage supplied by the input circuit LC is impressed upon the control grid 6 only, while the variable control voltage source designated by Er is applied to the grid half 3' as well as to the second control grid 6, or the control voltage may be applied only to the grid 3'. In the first case, the controlling action will be more effective. In the lead to the grid half 3', a resistance W is inserted, in which the same radio frequency voltage will be developed as that in the 15 tuned circuit L1 C1. By exchanging the leads to the grid halves 3', 3'', it is possible to place the resistance W inside the tube, and to connect the same to the grid half 3'' and to the cathode, so that a special lead to the grid 3'' can be dispensed with.

While I have indicated the preferred embodiment of my invention of which I am now aware and have also indicated only one specific application for which my invention may be employed, 25 it is apparent that my invention is by no means limited to the exact forms illustrated or the use indicated, but that many variations may be made in the particular structure used and the purpose for which it is employed without departing from 30 the scope of my invention as set forth in the appended claims.

What I claim as new is,—

1. An electron discharge tube having a thermionic cathode, a grid electrode surrounding said cathode and provided with oppositely extending longitudinal fins, a plurality of grids and an anode positioned on one side of said cathode for providing a main discharge path between said cathode and said anode, an auxiliary anode placed on the 35 opposite side of said cathode from the main anode to provide a second discharge path between said cathode and said auxiliary anode, the fins on said grid shielding the two discharge paths from each other.

2. An electron discharge tube having a thermionic cathode, a grid electrode surrounding said cathode, a main anode positioned on one side of said cathode, a control electrode between said main anode and said cathode, and a box-shaped 50 electrode surrounding only said control electrode and permitting the passage of current between said cathode and said main anode, an auxiliary anode placed on the opposite side of said cathode from said main anode to provide a discharge path 55 between said cathode and said auxiliary anode.

3. An electron discharge tube having a thermionic cathode, a grid electrode surrounding said cathode, a main anode positioned on one side of said cathode, a control electrode between said main anode and said cathode, and a box-shaped 60 electrode surrounding said control electrode, and an auxiliary anode placed on the opposite side of said cathode from said main anode, and a suppressor grid placed between said main anode and 65 the other electrodes in said discharge tube and surrounding all of the other electrodes in said tube.

4. An electron discharge tube having a thermionic cathode, a grid electrode surrounding said 70 cathode, a main anode positioned on one side of said cathode, a control grid electrode between said main anode and said cathode, and a box-shaped grid electrode surrounding said control electrode, and permitting the passage of electrons from said 75

cathode to the main anode, an auxiliary anode placed on the opposite side of said cathode from said main anode, and a suppressor grid placed between said principal anode and the other electrodes in said discharge tube and surrounding all of the other electrodes in said tube; one of the grid electrodes between said main anode and said cathode having a variable mu characteristic.

5. An electron discharge tube having a thermionic cathode, a grid electrode surrounding said thermionic cathode, a main anode positioned on one side of said thermionic cathode, a control electrode positioned between said cathode and said main anode and a screen electrode surrounding only said control electrode, and an auxiliary electrode positioned on the other side of said cathode from said main electrode whereby oppositely extending discharge paths are provided between said cathode and the anodes.

6. An electron discharge tube having a thermionic cathode, a grid electrode surrounding said thermionic cathode, a main anode positioned on one side of said thermionic cathode, a control electrode positioned between said cathode and

said main anode, a screen electrode surrounding said control electrode; an auxiliary electrode positioned on the other side of said cathode from said main electrode whereby oppositely extending discharge paths are provided between said cathode and the anodes, and a suppressor grid positioned between said main anode and the other electrodes in the tube and surrounding all of the other electrodes within said tube.

7. An electron discharge tube having a thermionic cathode, a grid electrode surrounding said cathode, a main anode positioned on one side of said cathode, a control electrode between said main anode and said cathode, an auxiliary anode placed on the opposite side of said cathode from said main anode whereby two oppositely disposed electron discharge paths are provided between said cathode and said anodes; and oppositely disposed longitudinal fins extending outwardly from said grid electrode, said fins being positioned perpendicularly to the electron discharge paths between said cathode and said anodes to shield the two electron discharge paths from each other.

KARL STEIMEL.
